UNITED STATES PATENT OFFICE.

OSCAR HAYES, OF DENVER, COLORADO, ASSIGNOR TO THE HAYES MANUFACTURING COMPANY, OF DENVER, COLORADO, A CORPORATION OF COLORADO.

VAPOR FORMING AND INJECTING DEVICE FOR GAS-ENGINES.

1,244,731.

Specification of Letters Patent. Patented Oct. 30, 1917.

Application filed May 19, 1916. Serial No. 98,577.

To all whom it may concern:

Be it known that I, OSCAR HAYES, a citizen of the United States, and a resident of the city and county of Denver, in the State 5 of Colorado, have invented certain new and useful Improvements in Vapor Forming and Injecting Devices for Gas-Engines, of which the following is a full, clear, and exact description, such as will enable others skilled 10 in the art to which the invention appertains to make and use the same.

The invention relates to improvements in attachments for gas engines for forming a vapor of water and injecting the same 15 into the cylinders of the engine with the carbonaceous fluid.

The object of the invention is to provide means for effecting a more efficient and volatile motive fluid compound and for diminishing the amount of carbonaceous fluid 20 necessary to be used otherwise.

Another object of the invention is to provide means for effecting a motive fluid mixture having a maximum degree of expansion 25 qualities after ignition.

Another object of the invention is to provide a device of the class specified which may be conveniently and quickly applied to any gas engine without the necessity of employing cumbersome and complicated attachments.

Another object of the invention is to provide a device of the class described in such form and construction as to make a standard article of general application and use 35 in connection with any form, or make of gas engine.

Another object of the invention is to provide a device of the class described of extremely simple construction, positive operation and durability.

With these and other objects in view, the invention will now be described with reference to the accompanying drawing, forming 45 a part hereof.

In this drawing, Figure 1 is an end view of the device; Fig. 2 is a cross sectional view, taken on the line 2-2 of Fig. 1; and Fig. 3 is a cross sectional view taken on the 50 line 3-3 of Fig. 2.

Corresponding and like parts are referred to in the following description and indicated in all the views of the accompanying drawing by the same reference characters.

55 Let the numeral 5 represent an exhaust

pipe of a gas engine to which the water volatilizing chamber 6 is attached. My invention resides in the construction and application of this volatilizing chamber 6 to the engine, and for the purpose of illustrating and describing my invention, the drawing is confined to an illustration of the said volatilizing chamber and its application. This chamber comprises an outer tubular housing 7 and a valve sleeve 8, which is received in the outer housing 7, the forward extremity of the latter being open to receive said valve sleeve therein. The inner extremity of the tubular housing 7 is provided with a screw plug 9 integrally formed therewith adapted to be threaded into an opening 10, which is formed in the exhaust pipe 5, thereby providing means for attaching the device to the exhaust pipe of the engine in such position that the heat of the 75 said exhaust pipe is employed for volatilizing water which is introduced into the chamber 6 from a source of water supply in the manner hereinafter to be described. The outer extremity of the valve sleeve 8 is 80 closed to the outer atmosphere, while the inner extremity thereof is open and abuts against the inner extremity of the housing 7. Thus, the water volatilizing space is formed on the interior of the valve sleeve 8, 85 the said space being housed by the valve sleeve 8 and the latter being in telescoping relation with the housing 7. The valve sleeve 8 is revolubly mounted in the housing 7, and the same is machined to snugly fit 90 into the housing 7.

An induction pipe 12, which is in communication with the radiator of the engine, or other suitable source of water supply, is in communication with an induction port 95 13 in the housing 7, the said induction port 13 adapted to register with an induction port 14 in the valve sleeve 8. An eduction pipe 15 is in communication with an eduction port 16 of the housing 7, which said 100 eduction port 16 is adapted to register with an eduction port 17 of the valve sleeve. The eduction pipe 15 communicates with the cylinders of the engine, whereby the volatilized water is conveyed, or injected into the 105 latter through said pipe. A bolt 18 is passed through the outer extremity of the valve sleeve 8 and the inner extremity of said bolt is threaded into the inner end of the housing 7, as shown at 19, thereby connecting the 110

valve sleeve 8 in fixed relation with the said housing 7. The outer extremity of the valve sleeve 8 is provided with an annular flange 20 thereon, which extends beyond the circumference of the said valve sleeve and engages with the outer extremity of the housing 7. The periphery of this annular flange 20 is provided with a gap 21 therein, in which is received a pin 22 projecting from the outer extremity of the housing 7. Thus, the valve sleeve 8 can only be rotated the length of the said gap 21, the pin 22 forming a stop to further rotation thereof. This rotary movement of the valve sleeve 8 is only sufficient to register the ports 14 and 17 of the valve sleeve 8 with the ports 13 and 16 of the housing 7. As illustrated in Fig. 3, these ports are now out of register and the pin 22 engaged at one extremity of the gap 21. Thus, by moving the valve sleeve 8 in the direction indicated by the arrow, the said ports will be brought into register. For the purpose of operating the valve sleeve 8, an operating member 24 is connected at one extremity with an ear 25, formed on the periphery of the annular flange 20, the said operating member 24 being extended through a guide member 26 into convenient reach of the operator of the engine. This guide member 24 is integrally formed with the housing 7 near the outer extremity of the latter, as shown at 27. The induction pipe 12 is controlled by means of a valve piece 28, which is-threaded into the said induction pipe, as shown at 30, whereby the flow of water through said pipe into the valve sleeve 8 is regulated according to the proper amount to effect the best results.

40 The inner extremity of the housing 7, adjacent the exhaust pipe 5, is provided with an air induction opening 31, which said opening is constantly open and takes air therein from adjacent the exhaust pipe, the air being of a high temperature previous to entering the opening 31 as a result of the influence of the heat from the exhaust pipe.

Now, assuming that the valve piece 28 is in open position and that the ports 13 and 14 and 16 and 17 are in registering positions, water will flow through the ports 13 and 14 into the valve sleeve 8, wherein it will be volatilized under the temperature of the said chamber, due to the influence of the heat from the exhaust pipe 5. This volatile water will now pass from the volatilizing chamber 6 through the registering eduction ports 17 and 16 and pipe 15 into the cylinders of the engine, where it is properly mixed with the carbonaceous fluids, the volatile water being injected into the cylinder slightly in advance of the carbonaceous fluid, or compound.

65 By placing the volatilizing chamber 6 in

close proximity to the exhaust pipe 5, the heat of the latter maintains a relatively high temperature in the vicinity of said chamber sufficient to instantaneously volatilize the water on entering the said chamber. 70

While I have described and illustrated herein a specific form of my invention, it is understood that I am not limited thereto and that the same may be modified and varied without departing from the spirit of the invention, or the scope of the appended claims. 75

Having thus described my invention, what I claim and desire to secure by Letters Patent is:

1. A device of the class described, comprising a housing, a valve sleeve telescoping in said housing and rotatable therein, the housing and valve sleeve having induction ports for the induction of water and eduction ports for the eduction of vapor, means for operating said valve sleeve to cause its induction and eduction ports to respectively register with the induction and eduction ports of the housing, and said housing having a separate air induction port. 85

2. A device of the class described, comprising a housing, a valve sleeve telescoping with said housing and forming a chamber within said valve sleeve, the housing having a plug thereon adapted to engage with the engine for sustaining the housing in place, the housing and valve sleeve having induction and eduction ports, means for moving said ports of the valve sleeve into and out of register with the ports of the housing, and said housing having a permanently open induction port for air. 95 100

3. A device for attachment to gas engines, comprising a housing open at one end, a valve sleeve open at one end and received in said housing, its open extremity being protruded in the housing adjacent the closed extremity of the latter, the housing and valve sleeve having induction and eduction ports, means for moving the valve sleeve to cause the ports thereof to register with the ports of the housing, and the closed extremity of the housing having a permanently open air port. 110 115

4. A device of the class described for attachment to gas engines, comprising a housing open at one extremity and closed at the other extremity, a valve sleeve open at one extremity and closed at the other extremity, the open extremity of the valve sleeve being telescoped in the housing and abutting against the closed extremity of the latter, a bolt passing through the closed extremity of the valve sleeve and connected with the housing for holding the valve sleeve in fixed relation with the housing, the housing and the valve sleeve having in- 120 125 130

duction and eduction ports, means for moving the valve sleeve to cause the ports thereof to register with the ports of the housing, and means for limiting the movement of the valve sleeve when the said ports are in register.

5. A device of the class described for attachment to gas engines for volatilizing water and mixing same with the carbonaceous fuels, comprising a housing attached to the engine in the vicinity of relatively high temperature, a valve sleeve telescoping with said housing and forming a volatilizing chamber on the interior thereof, means for holding said valve sleeve in fixed relation with said housing, the valve sleeve being movable in said housing, the housing and

the valve sleeve having induction and eduction ports, means for moving said valve sleeve to cause said induction ports and 20 eduction ports to register, the outer extremity of the valve sleeve having an annular flange thereon engaged by the outer extremity of the housing, said flange having a 25 gap therein, and the housing having a part received in said gap for limiting the movement of the valve sleeve.

In testimony whereof, I affix my signature in the presence of two witnesses.

OSCAR HAYES.
